INVENTOR

Charles H. Morrill
By his Attorney,
Nelson M. Howard

UNITED STATES PATENT OFFICE.

CHARLES H. MORRILL, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY.

LAST.

Application filed October 18, 1920. Serial No. 417,712.

This invention relates to the manufacture of arctic shoes and is disclosed for illustrative purposes as embodied in a so-called arctic-last set for use in the manufacture of 5 rubber shoes or arctics.

Lasts or forms of this type are manufactured in a number of different lengths of leg, and it has heretofore been the custom to provide complete lasts for each length. Owing 10 to the expense and difficulty of obtaining and handling large blocks of wood, they have sometimes been made in two pieces, a leg portion and a foot portion, the two portions being then fastened firmly and permanently 15 together in the course of manufacture of the last. I have discovered that the lasts used, for example, in making 1, 4 and 6 buckle arctics all have a substantially identical lower foot portion differing only in the 20 shape of the portions above the ankle, and that a great saving in investment and storage room and labor in manufacture can be made by providing a single foot portion adapted to receive interchangeably several 25 detachable leg portions, with which the foot portion may be used at will. Accordingly an important feature of the invention consists in a last set characterized as above described. 30 This and other features of the invention comprising certain combinations and arrangements of parts will be understood from the following description of a preferred embodiment thereof selected for purposes of illustration and shown in the accompanying 35 drawings in which,

Fig. 1 is a diagram showing the operative relation of the different leg portions to the foot portion, and

Figs. 2 and 3 show the 1 and 4 buckle leg 40 portions detached.

In Fig. 1 the full line outline shows a last for a 6-buckle arctic. This is made in two pieces, a leg portion 10 and a foot portion 12, separable along the line 14 and rigidly held 45 together when attached to each other by a latch 16 operable by a handle 18 at the top of the leg, and engaging a slotted plate 20 in the foot portion. Dowels 22 are provided on one of the parts to engage holes in the other to hold the parts in alinement. The last parts are thus obviously readily separable 50 when desired.

The foot portion 12 is of the ordinary 55 form used in these lasts, but has its upper surface 14 near the ankle, in the locality

where the outlines of the leg portions used in the lasts of different heights begin to diverge from one another as explained below. The upper cross-section of the foot portion is common to all lasts of a set. 60

A "set" as herein defined may consist of a foot portion and a convenient number of leg portions of varying heights. The style of the foot portions of lasts of the type herein illustrated is not determined by the leg portions, since changes in style, as far as the last is concerned, affect only the forepart of the foot portion, the leg portions being the same irrespective of the style. Accordingly, a set may also consist of a plurality of foot 70 portions of varying styles, but of the same size and width, or foot-room, plus a convenient number of leg portions of varying heights. 75

As to such a last of given size and style, the shape of the lower portion of the last is invariable from the tread face up to about the level of the ankle joint, irrespective of the height of the leg portion. From this point up, however, the vertical profile of the 80 last begins to differ materially, for the reason that the portion of the leg of a shoe such as an arctic just above the ankle must be loose owing to the necessity of drawing the heel and instep of the shoe worn inside the 85 arctic through this portion of the arctic in putting it on and off. In the foot portion of the arctic as far up as the ankle portion, the heel of the wearer's shoe can rise straight up far enough to free itself (and vice versa), 90

but just above this point room, in addition to the room required by the lower part of the wearer's leg and that furnished by such bellows-tongue construction as it is practical to put in an arctic, is required to allow the 95 shoe heel to pass. This additional room varies somewhat with the height of the leg portion of the arctic and the distance the shoe heel has to move in being pulled out. In particular, the difference between the 1- or 2-buckle arctic, the 4- or more buckle arctic is considerable. The upper end of the arctic is made to fit the leg of the wearer and the shape of the arctic leg tapers down from there to the dimension required above 100 the ankle. This results in a radically different leg-profile in shoes of different heights, as shown in Fig. 1.

In accordance with the present invention, the joint 14 between the foot and leg por- 110

tions is made at or below the point where the vertical profiles of the leg portions begin to diverge, so that the foot portion will fit perfectly with any leg portion. A 1-buckle leg portion is shown at 26 in Fig. 1 and in Fig. 3. A 4-buckle leg portion is shown at 24 in Fig. 1 and in Fig. 2. A 6-buckle leg portion is shown at 10 in Fig. 1.

Thus, by the present invention, an arctic maker need keep much less capital tied up in foot portions than he must in accordance with prior practice, for the same manufacturing capacity, since he can use the same stock of foot portions all the time, irrespective of the heights of the legs of the shoes he is making. Also, the foot portion is the more expensive part of the last.

In addition to this capital economy, the manufacture of the shoes is simplified by the detachability of the last portions which is secured by the present invention. Formerly the whole last was always used in one piece and the weight of it wearied the operator very much. Also, a long legged last militates against machine operations on shoes such as arctics, as the handling of the arctics for such operations involves turning the shoe in a limited space, and a long leg portion in the last interferes with such procedure. When using last apparatus constructed in accordance with the present invention, the manufacture of the shoe may be completed up to the vulcanizing operation upon the foot portion alone, the leg portions of the shoes being cut by pattern, assembled and left to hang as do the corresponding parts of a leather boot. In such use the pins on the "stick" on which the shoes are carried around the factory are placed in the holes which later accommodate the dowels 22. If the practice just outlined is followed, when the shoe is ready for the vulcanizing operation, the leg portion of the last is inserted and the shoe properly arranged on it, and the vulcanization shapes the whole shoe to the whole last.

There is thus secured a distinct economy of effort in hand work and the advantage of adaptability for machine operations, if desired.

Having described my invention, what I

claim as new and desire to secure by Letters Patent of the United States is:

1. A set of last apparatus for the manufacture of arctics comprising a foot portion and a plurality of leg portions of different vertical profiles constructed and arranged to co-operate interchangeably with the foot portion, the surface of separation of each of said leg portions being of the same shape and dimensions as the surface of separation of the foot portion, and means for detachably and rigidly securing a leg portion to said foot portion with their surfaces of separation registering.

2. A set of last apparatus comprising a foot portion extending upward to substantially ankle-height and a plurality of leg portions of varying vertical profiles constructed and arranged to co-operate interchangeably with the foot portion.

3. A set of arctic last apparatus comprising a foot portion and a plurality of leg portions of varying heights, each arranged to join the foot portion separably along a line low enough in the last to be in that part of the last which is of the same dimensions in all arctic lasts of that size having varying heights of leg portion, whereby the foot portion may be used with any leg portion of the set to form a complete last.

4. An arctic last set comprising a foot portion having a surface of separation along a line at the point where leg portions of different heights begin to diverge from one another, and a set of leg portions of varying heights constructed and arranged to be interchanged with each other in detachable combination with the foot portion at the said surface of separation.

5. An arctic last set comprising a foot portion having a surface of separation along a line at about the location of the ankle where leg portions of different heights begin to diverge from one another, and a set of leg portions of varying heights constructed and arranged to be interchanged with each other in separable combination with the foot portion at the said surface of separation.

In testimony whereof I have signed my name to this specification.

CHARLES H. MORRILL.
